UNITED STATES PATENT OFFICE.

CHARLES VEHRING, OF BROOKLYN, NEW YORK, ASSIGNOR TO LEVI LIVINGSTON, BENJAMIN LIVINGSTON, AND SOLOMON LIVINGSTON, OF NEW YORK, N. Y.

DESIGN FOR A BELT-BUCKLE.

SPECIFICATION forming part of Design No. 34,126, dated February 26, 1901.

Application filed January 17, 1901. Serial No. 43,670. Term of patent 3½ years.

To all whom it may concern:

Be it known that I, CHARLES VEHRING, a citizen of the United States, residing in New York city, borough of Brooklyn, State of New York, have invented and produced a new and original Design for Belt-Buckles, of which the following is a specification, reference being had to the accompanying drawings, forming part hereof, wherein—

10 Figure 1 is a front view of my design for belt-buckles, and Fig. 2 is a cross-section on the line $x-x$ in Fig. 1.

The leading feature of my design consists in a pair of buckles located substantially side by side and extending at an obtuse angle relatively to each other to receive the opposite ends of a belt or strap and connected by an intermediate strip, the face of the buckles and the strip being exposed in front elevation.

20 In the accompanying drawings the buckles are indicated by the letters A B, and the inter-

mediate strip connecting said buckles is indicated by the letter C. The buckles are located substantially side by side and extend outwardly from the strip C at an obtuse angle relative to each other. In minor details the strip C is shown provided with a concave edge at c and a convex edge at c^2 between the buckles. 25

D is a band located between the buckles 30 and extending vertically over the front face of the strip C in the form of a loop, the buckles relative to the plane of the band forming an acute angle therewith on opposite sides thereof. 35

What I claim is—

The design for a belt-buckle, substantially as shown and described.

CHAS. VEHRING.
